UNITED STATES PATENT OFFICE.

WILLIAM B. WOLF, OF WALNUT, ILLINOIS, ASSIGNOR OF ONE-HALF TO
ISAAC KELLY, OF SAME PLACE.

CHECK-ROWER.

SPECIFICATION forming part of Letters Patent No. 247,727, dated September 27, 1881.

Application filed February 28, 1881. (No model.)

To all whom it may concern:

Be it known that I, WILLIAM B. WOLF, a citizen of the United States, residing at Walnut, in the county of Bureau and State of Illinois, have invented certain new and useful improvements in Check-Rowers; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

My invention has reference to an improvement in check-rowers for corn-planters, and relates more particularly to a novel pulley to engage and to be actuated by the usual knotted rope or wire, and also certain new devices between such pulley and the seed-discharging mechanism of the seed-hoppers, by which the partial rotations of such pulley are communicated to the seed-discharging plates of the seed-hoppers.

The invention, as shown, is intended for application to the well-known two-horse corn-planter, which plants two rows at the same time. As the general construction and material parts of such planters are well known in the art, I do not deem it necessary to exhibit or describe the same any further than to show the mode of attaching my invention.

In the drawings, Figure 1 is a rear elevation of a machine embodying my invention. Fig. 2 is a detached view of the lower face of the crank-wheel L and the upper side of the slotted plate O. Fig. 3 is an end view of the pulley D.

Fig. 1 exhibits the general frame-work and construction of my invention, and, as there shown, it is seated between the two seed-hoppers of the corn-planter transversely of the planter, and fastened to the latter in any suitable way.

A A are vertical posts, having their lower ends bolted to the usual board or plank, A', which extends across the planter from one seed-hopper to the other. In the upper ends of the posts A A is journaled the revolving transverse shaft C. On each end of the shaft C is placed a pulley, D, but one of which is

shown. The pulley D proper is placed loosely on the shaft C, so as to revolve thereon. On each side of the pulley D is affixed rigidly to the shaft C the clutch P, having the four points a, which latter extend beyond the periphery 55 of the pulley D, and are adapted to engage and be operated by the ordinary knotted rope or wire, which is stretched across the field parallel with the line of the movement of the planter. Near the center of the shaft C is rigidly 60 affixed thereto the vertical bevel-wheel E, which engages the smaller horizontal bevel-wheel F, the latter being attached rigidly to the upper end of the vertical shaft G. The shaft G is journaled through the cross-plate H. 65 To the lower end of the shaft G is rigidly affixed the crank-wheel L, on the lower face of which is the crank or wrist pin M.

N is the ordinary reciprocating bar, which extends from one seed-hopper to the other, and 70 actuates the seeding devices in and below such hoppers.

O is a plate fixed transversely on the bar N, near the center of the latter, and having the slot d lengthwise in its upper surface. The 75 wrist-pin M is fitted to engage the slot d of the plate O, and thus actuate the bar N and the seeding devices in each seed-hopper connected thereto.

The bevel-wheel E has double the number 80 of cogs that the wheel F has, so that one revolution of the former gives two revolutions to the latter. Each revolution of the wheel F causes two full motions of the reciprocating bar N. The forks a of the clutch P are so arranged and located that each knot upon the cord or wire will revolve the clutch, and thus the wheel E, one-fourth of a revolution, which gives one motion to the bar N and drops one hill of corn from each of the seed-hoppers. The 85 knots upon the cord or wire are such distance apart as it is desired the hills of corn may be between the check or cross rows.

The sizes of the pulley D, clutch P, and wheels E and F may be varied; but the proportions 95 mentioned will need to be observed.

The pulley D has a groove extending around its periphery to carry the knotted cord. The object in having the pulley D revolve independent of the clutch P is to avoid the fri- 100

tion of drawing the rope or wire over the pulley, and thus save the wear of both the pulley and rope or wire.

The slot *d* may be made with both ends closed; but I prefer the open ends, as thus any dirt falling therein can work out. So a simple crank might be substituted for the crank-wheel *L*; but the latter gives greater strength and more momentum.

20 Guide-pulleys can be placed in the usual way at the ends of the shaft *C*, to guide the knotted rope to and from the pulley *D*.

I am aware that a wheel having a wrist-pin adapted to engage with a slotted guide on the seed slide or dropper for operating the same, and also two disks having lugs with which a knotted check-row wire or cord engages, with an intermediate loose pulley, are common in check-rowers, and such I do not wish to be understood as claiming, broadly, as of my invention.

What I claim as my invention, and desire to secure by Letters Patent of the United States, is—

In a check-rower, the combination of the 25 shaft *C*, provided with the loose pulley *D*, clutch *P*, having the points *a*, and the bevel-wheel *F*, vertical shaft *G*, provided with the bevel-wheel *F*, and wheel *L*, provided with crank or wrist pin *M*, and the seed slide or bar *N*, provided 30 with the slotted guide *O*, the several parts constructed and relatively arranged to operate substantially in the manner as and for the purpose herein shown and described.

In testimony whereof I affix my signature 35 my presence of two witnesses.

WILLIAM B. WOLF.
